 Company, Incorporated, New York, N. Y., a cor-
 poration of New York

Application February 19, 1946, Serial No. 648,689

22 Claims. (Cl. 18—16)

1

This invention pertains to control systems for molding presses, and in particular to such systems for controlling the operation of angle molding presses.

One object of the invention is to provide a hydraulic-electrical control system for the automatic operation of an angle molding press.

Another object is to provide a control system which is highly efficient in automatically effecting selective operation of the vertical and horizontal rams of the press through various cycle portions at different speeds and at predetermined time intervals.

Another object is the provision of a low pressure, high volume pump to obtain fast operation of a hydraulic ram and a high pressure, low volume pump to obtain low speed operation of the ram for actual molding operation in cooperation with means for rendering one of the pumps ineffective upon the occurrence of a predetermined condition.

Another object is the provision of selective controls for hand and cycling operations and of an interlocking protective system to permit either selective manual operation or automatic cycling operation of the rams.

Another object is to provide a controlled timing system for an angle molding press whereby the molding die is closed by the rams to subject the molding material therein to a predetermined pressure and then one of the rams retracts a desired distance to permit breathing for the escapement of gases from the molding die and subsequently again reverses to apply an increased molding pressure until the end of the cure of the molded article. This feature of breathing the molding die is of particular advantage in the molding of synthetic resin materials and similar chemical compounds where the breathing period expedites the proper distribution of the molding materials in the die, permitting the escapement of gases and thus insuring solid molded articles of uniform quality.

Another object is to provide safety switches in the electrical control system to limit the out and down travel of the horizontal and vertical rams to prevent damage to the press.

With these and other objects in view, the invention comprises an interlocking selective control system, particularly for angle molding presses wherein the movements of the horizontal and vertical rams of the press are controlled by the admission and release of pressure fluid supplied by a low pressure, high volume pump and a high pressure, low volume pump by means of pilot con-

2

trolled valves operated by electric solenoids, the latter being energized and deenergized by an electrical system to provide various speeds of operation of the rams and to control their movements at predetermined intervals.

Other objects and advantages will be apparent from the following detailed description when considered in conjunction with the accompanying drawings, wherein:

Fig. 1 is a fragmentary front elevational view of an angle molding press equipped with a three part molding die and showing limit switches controlling the out and down movements of the horizontal and vertical rams respectively;

Fig. 2 is a diagrammatic view of the fluid pressure system for controlling the movement of the horizontal and vertical rams of the angle molding press of Fig. 1;

Figs. 3, 4, and 5 constitute a wiring diagram illustrating the electrical control system for the structures shown in Figs. 1 and 2, and

Fig. 6 is a perspective view of part of a phenol plastic mounting strip made in a three part molding die on the angle molding press of Fig. 1 controlled by the present invention.

Referring now to the drawings, attention is first directed to Fig. 1 which illustrates an angle molding press designated generally by the reference numeral 10. This angle molding press includes a case steel base 11 to which are secured four columns or posts 12 which carry a crown or head 13. The two left posts 12 are housed within a vertical steel strut 14 which is held in accurate alignment by keyways 15 at junction points with the head 13 and base 11. Mounted centrally in the head 13 is a vertical hydraulic cylinder 16 which contains a reciprocable piston 17 secured to a ram 18 (Figs. 1 and 2).

A cross head 19 having a flange 20 is secured to the vertical ram 18. This flange is machined and brass lined and engages a vertical guide slot in the strut 14 to positively guide and align the ram in its up and down movement. Fastened to the under side of the cross head 19 on the vertical ram 18 is an upper part 21 of a three part molding die 22 for making the molded article or mounting strip 23 shown in Fig. 6. A left hand stationary portion 24 (Fig. 1) of the die 22 is held in proper alignment in a cross head 25 secured in the frame 11, and a movable right hand portion 26 of the die is secured in proper alignment in a cross head 27 secured to a horizontal ram 28. This horizontal ram of the angle molding press is secured to a piston 29 (Fig. 2) which is reciprocally mounted in a horizontal hydraulic cylin-

der 30 secured to the base 11 by any suitable means. A steel block 31 (Fig. 1) positioned on a bolster 32 on the bed of the press supports the die parts 24 and 26 when the three part die is closed under pressure to produce the molded mounting strip 23. As the press is to be used for molding thermosetting material, the horizontal ram 28 is generally used for closing and holding the die parts 24 and 26 closed, and the vertical ram 18 is used for applying the molding pressure through the third die part 21. Also suitable means (not shown) is provided for heating the molding die to cure the molded article.

Hydraulic system

The hydraulic or fluid pressure system for actuating the horizontal and vertical rams of the press includes an oil reservoir 35 (Fig. 2), two high pressure, low volume pumps 36—37 driven by a double end motor 38, a prefill or low pressure, high volume pump 39 driven by a motor 40, three four-way hydraulic valves 41, 42 and 43, which are solenoid controlled and pilot operated and interconnected by pipe lines to carry the oil under pressure as disclosed in Fig. 2.

Each of the four-way valves 41, 42 and 43 is spring centered, dual solenoid pilot operated with cylinder ports closed and supply port opened to exhaust in neutral position when both solenoids are deenergized. This construction permits unloading the pump volume back to the oil reservoir 35 during idle operation. These four-way valves are of standard well known construction and need not be described further.

The horizontal ram 28 is moved toward the left to "in" position to close the die parts 24 and 26 by the energization of a horizontal in advance solenoid 45 which operates a pilot valve 46 to shut its normal exhaust line 47 to the oil reservoir. High pressure oil then flows from pump 36 through pipe 48, pilot valve 46 and pipe 49 to actuate the four-way valve 41 to permit oil under low pressure and high volume to be fed from the tank 35 through low pressure pump 39, pipe 50, valve 41, pipe 51 into the right hand end of the horizontal cylinder 30. Simultaneously a solenoid 52 is energized to operate its pilot valve 53. Operation of this pilot valve closes its exhaust line 54 to the oil reservoir and high pressure oil then flows from pump 36 through pipe 55, pilot valve 53 and pipe 56 to actuate valve 42. The actuation of valve 42 causes high pressure oil also to be admitted into the right hand end of the horizontal cylinder 30 from the tank 35 through high pressure pump 37, pipe 57, valve 42 and pipe 58 into the cylinder 30 to move the ram 28 at high speed toward the left to "in" position.

The four-way valve 42 is so constructed that upon providing communication between the pipes 57 and 58, communication is also simultaneously established between an exhaust pipe 59 and a pipe 60 so as to allow the fluid on the left side of the piston 29 of the ram 28 to exhaust through the pipe 60, valve 42, pipe 59 to the oil reservoir 35.

As the horizontal ram 28 moves at high speed toward the left an arm 61 on a rod 62 secured to and movable with the ram 28 opens a normally closed limit switch 63 (Figs. 1, 2, and 4) which deenergizes horizontal in advance solenoid 45 to shut off the low pressure, high volume oil to the horizontal cylinder 30 and permit the ram 28 to continue to advance at slow or pressing speed under high pressure, low volume oil from the pump 37. The ram 28 moves to "in" position toward the left until the die parts 24 and 26 are closed when

another arm 64 fixed to the moving rod 62 operates a limit switch 65 which connects power to effect operation of the vertical ram 18. Another limit switch 66 operated by an arm 67 on the rod 62 controls the "in" travel of the horizontal ram 28 toward the left and limit switch 68 operated by the arm 61 controls the "out" movement of the ram 28 to the right to prevent damage to the press.

In controlling the movement of the vertical ram 18, electrical power is applied to energize a vertical down in advance solenoid 70 (Figs. 2 and 3) which operates its pilot valve 71. Actuation of the pilot valve 71 closes its exhaust line 72 to the oil reservoir 35 and causes oil under pressure to flow from pressure pump 36 through pipe 73, pilot valve 71, pipe 74, to valve 41 to cause operation thereof. This actuation of valve 41 admits low pressure, high volume oil from pump 39 through pipe 50, through valve 41 and pipes 75—76 into the top of the vertical cylinder 16.

A moment later vertical down solenoid 77 (Figs. 2 and 3) is energized to actuate valve 43. This operation of valve 43 also admits high pressure, low volume oil into the top of cylinder 16 from pump 36 through pipe 81, valve 43, pipes 82 and 76.

The low pressure, high volume oil flowing into the top of cylinder 16 causes the piston 17 and vertical ram 18 to move down at fast speed until limit switch 83 is operated by an arm 84 fixed to a vertical rod 85, which is secured to and travels with the vertical ram 18. Actuation of limit switch 83 deenergizes vertical down in advance solenoid 70 thereby returning valve 41 to neutral position and stopping the flow of the low pressure, high volume oil through pipe 75. The ram 18 continues downward under the influence of the high pressure, low volume oil at pressing speed and applies pressure on the molding die 22 until a timing device energizes a vertical up solenoid 82 to operate a pilot valve 89 which actuates the valve 43 to stop the flow of oil through pipes 82 and 16 and cause oil to flow through line 90 and foot valve 91 into the lower end of vertical cylinder 16 to move the ram 18 upward. The foot valve 91 is inserted in the pipe line 90 to maintain sufficient pressure under the vertical piston 17 to prevent the ram 18 from dropping under its own weight when the hydraulic system is not in operation.

The four-way valve 43 is so constructed that upon providing communication between pipe lines 82 and 16 to move the ram 18 downward, communication is also established with the inner lower end of cylinder 16 by the foot valve 91 and the pipe line 90 so as to allow the fluid below the piston 17 to exhaust to the reservoir 35. Also when the pilot valve 89 actuates the valve 43 to move the ram 18 upward, the valve 43 also provides communication therethrough between pipes 76, 82 and exhaust pipe 59 to permit the fluid above the piston 17 to exhaust to the reservoir 35.

A limit switch 92 is provided in the path of travel of the vertical ram to limit its downward movement and is operated by an arm 93 secured to the vertical arm 85 which moves with the vertical ram 18. Another limit switch 94 limits the upward movement of the vertical ram 18 and is likewise operated by the arm 93.

A horizontal "out" solenoid 95 is then actuated to operate its pilot valve 96 which operates valve 42 to stop the flow of oil through pipe 58 and cause oil to flow through the pipe 60 into the left hand end of horizontal cylinder 30 to move the

ram 28 to its "out" or right hand normal position when the press is ready for reloading and the next cycle. This operation of the valve 42 by the pilot valve 96, not only shuts off the flow of oil from pipe 57 to pipe 58 but also connects pipe 58 with exhaust pipe 59 so that the oil on the right side of the piston 29 can exhaust to the reservoir 35.

Press controls

The above described hydraulic functions of the press are controlled by the electrical system shown in Figs. 3, 4, and 5. There are two conditions to be satisfied in operating the press under different conditions; namely, hand and automatic cycling operations, these operations being so interlocked that they cannot be operated simultaneously. Hand operation involves moving either ram in either direction at slow speed as long as a contact button for the function desired is held depressed and so interlocked that only one function can be accomplished at a time.

Automatic cycling operation must satisfy four conditions; angle molding, with or without breathing, involving both horizontal and vertical rams, and standard vertical molding with or without breathing and the horizontal ram inactive.

Automatic cycling under the first condition with the breathing function involves the following sequence of operations: depressing a button causes the horizontal ram to move in at fast speed to a predetermined point where the speed is reduced and the die is closed to set up controls for operation of the vertical ram. Depressing a second button causes the vertical ram to move down at fast speed to a predetermined point where speed is reduced and the die closes at slow speed. Pressure is built up in the mold to the desired degree. The vertical ram then reverses and moves up a short distance, sufficient to allow the mold to breathe. The vertical ram reverses again and moves down to apply molding pressure until the end of the cure. The ram then moves up to the end of its upward travel and the horizontal ram opens the die by returning to its outward limit, and the cycle is completed.

The same cycle without breathing involves the selective omission of the short upward movement of the vertical ram.

Standard operation with vertical ram only involves selective operation as above for breathing, and a positive lock out of the horizontal ram function.

The electrical control system and operation of the press

Assuming that the press is in its open or normal position as shown in Figs. 1 and 2, the closing of a main switch 100 (Fig. 3) energizes a relay 101 which closes its contacts 102-106 to a 440 volt A. C. power supply, indicated at 107. The closing of the contacts 105-106 establishes an energizing circuit through the primary winding 108 of a step down transformer 109. A secondary winding 110 of the transformer supplies 110 volt A. C. power to lines 111 and 112 (Figs. 3 and 4). A conductor 113 connected across the power lines 111 and 112 lights a green pilot lamp 114 to indicate that the transformer is delivering power. Closure of switch 115 (Figs. 1 and 3) turns on a plurality of machine lights 116 through a conductor 117 to provide proper vision for the operator.

The operator then momentarily presses a start button 118 (Figs. 1 and 4) to on position to energize a main motor relay 119 through a circuit 75

from power line 111 through the closed contacts of the start button 118, conductor 121, the winding of relay 119, conductor 122 back to powerline 112. Also a pilot light 120 is lighted from power line 111 through the closed contacts of start button 118, conductor 121, conductor 123, through the pilot light 120 back to powerline 112. Operation of the relay 119 closes its contacts 124 (Fig. 3) to effect operation of the double end main pump motor 38 (Figs. 2 and 3) from the source of power 107 through closed contacts 102-104 and conductors 126, 127 and 128. The main motor relay 119 is maintained energized through its own interlock contact 129 and conductor 130.

Manual control

Hand control only is possible at this point since the power lines 111-112 from the transformer 109 are broken at open contacts 131-132 (Fig. 4). To obtain hand control of the press, a hand lock switch 133 is closed by the operator to establish hand control circuits 134, 135, 136 and 137 (Fig. 4) through normally closed contacts 138, 139 and 140 of unoperated automatic control relays 141, 142 and 143, respectively. Also a red pilot lamp 145 is lighted from power line 111 through closed lower contacts 146 of operated switch 133, closed contacts 138, conductor 147, through the red pilot lamp 145 back to powerline 112. This red light indicates that the press is now set up for hand control. At the same time, automatic operation of the press is rendered impossible by the opening of top contacts 148 of switch 133 when it was depressed to set up hand control.

If it is desired to move the horizontal ram 28 to the "in" or left position under hand control, the operator depresses button switch 152 (Fig. 4) and holds it closed whereupon a circuit is established from power line 111 through contacts 146 of locked switch 133, normally closed contacts 138 of cycle control relay 141, normally closed contacts 139 of vertical control relay 142, closed limit switch 66, closed contacts of manually operated button switch 152, through the winding or "inch horizontal in" relay 153 (Fig. 4), normally closed contacts 154, 155 and 156 of inch horizontal out relay 157, inch vertical down relay 158 and inch vertical up relay 159, respectively, then through conductor 134 to power line 112. Energization of relay 153 closes its normally open contacts 160 (Fig. 3) to operate horizontal in solenoid 52 from power line 128, conductors 164-165, through the winding of horizontal in solenoid 52, closed contacts 160, conductors 166-167 back to power line 126. Operation of the solenoid 52 (Figs. 2 and 3) effects the "in" slow or inch operation of the ram 28 to the left. Release of pressure on the button 152 by the operator immediately interrupts the function and horizontal ram 28 can be stopped in any position.

Likewise the operation of horizontal out button switch 170, and vertical up button 171 (Figs. 1 and 4), or a vertical down button 172 will establish a particular circuit to energize a desired one of the relays 157, 158 or 159 to close contacts 161, 162 or 163 in Fig. 3 to operate a desired one of a plurality of solenoids 95, 77 or 88 which operate the horizontal or vertical rams in the manner hereinbefore described for the hydraulic system. The relays 153, 157, 158 and 159 are interlocked in a conventional manner as shown in Fig. 4 so that only one can be energized and operated at a particular time. The limit switches 66 and 92 are inserted in series with relay 152 and solenoid

158 to limit the "out" and "down" travel of the horizontal and vertical rams 28 and 18, respectively, to prevent damage to the press.

Automatic cycling operation with breathing

To obtain automatic operation of the press with breathing of the molding die 22, the horizontal ram 28 must be completely withdrawn to its "out" or right position so that contact 183 of limit switch 68 is closed before the start of operations. Also the vertical ram 18 must be in its full up position to operate switch 94. With this presetting of the press and the hand control switch in the off position, the operator then closes cycle lock button switch 180 (Figs. 1 and 4) which energizes the cycle control relay 141 from power line 111 through closed contacts of an emergency switch 181, the lower closed contacts 182 of operated lock switch 180, a normally closed contact 183 of limit switch 68, the winding of relay 141, closed contact 184 of the unoperated horizontal control relay 143, and conductor 185 to power line 112. Cycle control relay 141 is maintained energized through a locking circuit from the power line 112 through conductor 185, closed contact 184, the winding of relay 141, back through its now closed contact 186, conductor 179, closed contacts of emergency switch 181 to power line 111. Energization of the cycle control relay 141 opens its contact 138 and renders the hand control inoperative and closes contacts 131 and 132 to connect power to lines 187-188 of the automatic control circuits of Figs. 4 and 5. The operation of relay 141 also closes its contact 189 to connect power to circuits for controlling the horizontal and vertical cycling of the horizontal and vertical rams of the press. The establishment of power to lines 187 and 188 lights a green lamp 190 through conductor 191, which green light indicates that power is established for automatic operation.

The cycle lock switch 180 is returned to off position. The operator then momentarily depresses horizontal ram control button switch 192 (Figs. 1 and 4), to energize the horizontal in advance relay 193 (Fig. 4) from power line 111, through closed contacts 148 of unoperated hand control switch 133, upper closed contacts 194 of cycle lock switch 180, closed contacts 189 of cycle control relay 141, conductor 195, closed contacts of operated horizontal control switch 192, normally closed contacts 196, 197 and 198 of unoperated vertical control relay 142, horizontal out relay 199, and vertical down relay 200, the winding of relay 193, through a normally closed contact 201 of unoperated vertical up relay 202 (Fig. 5), conductor 203 to power line 188. The relay 193 is maintained energized through a lock up circuit from power line 187 through normally closed limit switch 63, conductor 204, now closed contacts 205 of the energized relay 193, the winding of relay 193, closed contact 201, conductor 203 to power line 188. A normally open contact 206 on relay 193 closes thereby energizing the fill motor relay 207 from power line 187 through conductor 208, closed contact 206, conductor 209, the winding of relay 207, the closed contact 210 of previously energized main motor relay 119 to power line 188. The fill motor relay 207 is maintained energized through a locking circuit from power line 188, through closed contact 210, the winding of relay 207, closed contact 211 of energized relay 207, conductor 212, the normally closed contact of limit switch 83 to power line 187.

Operated relay 207 closes its contacts 213 (Fig.

3) to connect power to fill pump motor 40 from source of power 107 through closed contacts 102-104, conductors 126-128, conductors 214, closed contacts 213, to motor 40 which operates high volume oil pump 39 (Fig. 2).

5 Energized relay 193 also closes its contact 215 (Fig. 3) thereby energizing the solenoid 45 of the horizontal in advance pilot valve 46 (Fig. 2) from power line 126 through conductors 167-166, closed contact 215 through the winding of solenoid 45 and conductor 164 to power line 128.

10 Also the operation of relay 193 closes its normally open contact 216 and energizes the horizontal in relay 217 from power line 187 through a normally closed contact 218 of vertical switch 219, conductor 220, closed contact 216, the winding of relay 217, conductor 221 to power line 188. Relay 217 is maintained energized through a locking circuit from power line 187, through closed contact 218, conductor 220, conductor 222, closed contact 223 of energized relay 217, normally closed contact 224, conductor 225, closed contact 226 of energized relay 207, conductors 227-228, the winding of relay 217, conductor 221 to power line 188.

25 Energized horizontal in relay 217 closes its contact 230 (Fig. 3) thereby energizing the solenoid 52 of the horizontal in pilot valve 53 (Fig. 2) from the power line 128, conductors 164-165, the winding of solenoid 52, closed contact 230, conductor 167 to power line 126.

30 This dual energization of solenoids 45 and 52 (Fig. 2) operates the pilot valves 46 and 53 respectively, which in turn operate the valves 41 and 42 to admit low pressure, high volume oil from pump 39 and high pressure, low volume oil from pump 37, respectively, to the right end of cylinder 30 through pipe lines as hereinbefore described for the hydraulic system to move the piston 29 and the horizontal ram 28 to the left or "in" position at fast speed.

35 The horizontal ram 28 moves forward on fast advance under the combined effect of the high volume delivery of the pump 39 and the low volume delivery of the pump 37 until limit switch 63 is operated by the arm 61 movable with the ram 28, whereupon switch 63 opens the locking circuit through the horizontal in advance relay 193. Relay 193 deenergizes and opens its contact 215 (Fig. 3) to deenergize the solenoid 45 of the pilot valve 46 to permit the valve 41 to return to neutral position thereby shutting off the high volume delivery of the pump 39 to operate horizontal ram 28.

40 The horizontal ram 28 continues to advance at slow or pressing speed under the effect of the high pressure, low volume delivery of pump 37 until the die parts 24, 26 are closed when limit switch 65 is closed by arm 64 (Fig. 2). The closing of limit switch 65 energizes a vertical lock out relay 231 (Fig. 4) from power line 187 through the winding of relay 231, closed limit switch 65, conductors 232-233 to power line 188. Relay 231 operates and closes its contact 234 (Fig. 5).

45 With horizontal in relay 217 still energized to maintain energization of solenoid 52 of pilot valve 53 which thus keeps valve 42 in position to continue to supply oil under pressure to the right side of piston 29 to maintain the horizontal ram 28 in "in" position to keep the die parts 24-26 closed. At this point molding material is introduced into the die and the operator momentarily depresses a cycle vertical button switch 235 (Figs. 1 and 5) which establishes an energizing circuit for a vertical down advance relay 236 (Fig. 5) 50 from power line 111 through normally closed up-

75 Operated relay 236 closes its contacts 237 (Fig.

per contacts 148 (Fig. 4) of unoperated hand control switch 133, through normally closed upper contacts 194 of unoperated cycle lock switch 180, closed contacts 189 of energized cycle control relay 141, conductor 195, conductor 231, closed contacts 234 of energized relay 231, upper closed contacts 229 of closed button switch 235, conductor 238, the winding of vertical down advance relay 236, normally closed contact 239 of unoperated vertical up relay 202, conductor 240 to power line 188. The vertical down advance relay 236 is maintained energized through a locking circuit from power line 188, conductor 240, closed contact 239, the winding of relay 236, conductor 241, closed contact 242 of energized relay 236, conductor 243 through closed limit switch 83 to power line 187.

Energized relay 236 closes its contact 246 thereby energizing solenoid 70 of the vertical down advance pilot valve 71 (Fig. 2) from power line 126 (Fig. 3) through conductors 167—166, contact 246, the winding of solenoid 70, conductor 164 to power line 128.

Another contact 245 (Fig. 5) of energized relay 236 is opened to prevent false up operation of vertical ram 18.

The momentary closing of the vertical cycle switch 235 also closes a circuit through the previously closed contact 234 of energized relay 231 to operate a timer 247 from power line 111 through upper closed contacts 148 of unoperated hand lock switch 133, the upper closed contacts 194 of unoperated cycle lock switch 180, closed contact 189, conductors 195, 231, closed contacts 234 of operated vertical lock out relay 231, closed contacts 244 of closed switch 235, normally closed contact 248 of an unoperated breathing out relay 250 (Fig. 5), conductor 251, the winding of the timer 247, conductors 252 and 253 to power line 188. The energization of the timer 247 effects the closing of its contacts 254 to create a locking circuit therefore from power line 111 through closed contacts 148 of switch 133, closed contacts 194 of switch 180, closed contact 189, conductors 195, 231, closed contact 234, through conductors 255—256, closed contacts 254, the winding of timer 247, conductors 252—253 to power line 188.

Energization of the timer 247 also closes its contact 257 to energize the vertical down relay 200 (Fig. 5) from power line 111, through closed contacts 148 of hand lock switch 133, upper closed contacts 194 of cycle lock switch 180, closed contact 189, conductors 195, 231, closed contact 234, conductors 255, 258 and 259, closed contact 257, the winding of vertical down relay 200, the normally closed contacts 260 of unoperated vertical up relay 202, conductor 261, to power line 188. Another contact 262 of operated timer 247 is opened to prevent operation of a timer 263 and false up operation of vertical ram 18.

Energized vertical down relay 200 closes its contact 264 (Fig. 3) thereby energizing down solenoid 71 to operate vertical down pilot valve 78 (Fig. 2) from power line 128 through conductor 164, the winding of down solenoid 71, closed contact 264, conductors 166—167 to power line 126.

This dual energization of down solenoids 70 and 71 operates pilot valves 71 and 78 (Fig. 2), respectively, which in turn operate the valves 41 and 43 to send oil under pressure through pipes 75 and 82 into pipe 76 to the upper end of vertical cylinder 16 to move the vertical ram 18 downward at fast speed. The ram 18 continues to move down at fast advance speed under the combined effect of the high volume delivery of

the pump 39 and the low volume delivery of pump 36 until limit switch 83 is tripped by arm 84, which operation of switch 83 opens the power from line 187 (Fig. 4) to deenergize the vertical down advance relay 236 by opening the locking circuit. Contact 246 (Fig. 3) of deenergized relay 236 then opens to deenergize vertical down advance solenoid 70 to permit valve 41 (Fig. 2) to return to neutral position thereby shutting off the high volume delivery of the pump 39.

The operation of limit switch 83 also opens the locking circuit to fill motor relay 207 which deenergizes and opens its contacts 213 (Fig. 3) to stop the operation of fill pump motor 40.

With the vertical down relay 200 still energized to maintain contact 264 (Fig. 3) closed and down solenoid 71 energized, pilot valve 78 remains operated to keep valve 43 in position to continue to supply oil under pressure to the upper side of

vertical piston 17. Thus vertical ram 18 continues down at pressing speed under the influence of the high pressure, low volume oil of pump 36 until die part 21 cooperates with closed die parts 24, 26 to apply pressure on the molding material.

Molding pressure is continued until the timer 247 times out after a predetermined interval. In the meantime, the operated vertical down relay 200 has closed its contact 267 to energize a control relay 268 from power conductor 195 through conductor 237, closed contact 234, conductor 255, conductor 258, conductor 269, closed contact 270 of limit switch 94 (Figs. 2 and 5), conductors 271—275, closed contact 267, the winding of control relay 268, conductor 273 to power line 188.

A locking circuit for control relay 268 is created from power line 188 through conductor 273, the winding of relay 268, its now closed contact 274, conductors 275, 276 and 271, normally closed contact 270 of up limit switch 94 (Figs. 2 and 5),

conductors 269, 258 and 255, closed contact 234 of the vertical lock out relay 231, conductors 237 and 195, closed contact 189 of the cycle control relay 141, the upper closed contacts 194 of the cycle lock switch 180, through the upper closed contacts 148 of hand lock switch 133 to power line 111. The energization of control relay 268 also closes its contacts 277, 278.

The operation of relay 268 also closes its contact 279 (Fig. 4) to maintain horizontal in relay 217 energized through a locking circuit from power line 188 through the conductor 221, the winding of relay 217, conductor 228, conductor 280, the closed contact 279, conductor 281, conductors 222, 220, the closed contact 218 of vertical switch 219 to power line 187. Thus through the continued energization of horizontal in relay 217, the horizontal ram is maintained in "in" position to keep the die parts 24, 26 closed until control relay 268 is deenergized.

After a predetermined interval, the timer 247 times out and opens its locking circuit through its contact 254 to deenergize its winding. Also contact 257 of timer 247 is opened to deenergize vertical down relay 200 which in turn opens its contact 264 to deenergize solenoid 71 (Fig. 3) to return valve 43 to neutral position and shut off the flow of high pressure oil into the upper end of vertical hydraulic cylinder 16 to release vertical ram 18.

At this point the winding of another timing mechanism 263 is energized from power line 188 through conductors 284—285, the winding of timer 263, conductors 286—287, a normally closed contact 288 of an unoperated control relay 289, closed contact 278 of energized control

relay 268, normally closed contacts 262 and 290 of the unoperated timer 247 and the breathing out relay 250 respectively, through conductors 291, 292, 258, 255, closed contacts 234 of energized vertical lock out relay 231, conductors 237, 195, through closed contact 189, closed upper contacts 194 of cycle lock switch 180, closed contacts 148 of hand lock switch 133 to power line 111. Operated timer 263 then establishes a locking circuit from power line 188 over conductors 284—285, through the winding of timer 263, its closed contact 293, conductors 294, 295, 291, 292, 258, 255, closed contact 234, conductors 237, 195, closed contact 189, upper closed contacts 194 of cycle lock switch 180, upper contacts 148 of hand lock switch 133 to power line 111.

Timer 263 starts timing and closes its contact 296 to energize vertical up relay 202 (Fig. 5) from power line 188 through conductor 297, the winding of relay 202, closed contact 296 of operated timer 263, normally closed contacts 298 and 245 of unoperated vertical down relay 200 and vertical down in advance relay 236, respectively, through conductors 300, 301, 276, 271, 25 closed contact 270 of up limit switch 94, conductors 269, 258, 255, closed contact 234 of energized vertical lock out relay 231, conductors 237, 195, closed contact 189 of energized cycle control relay 141, upper closed contacts 194 of unoperated cycle lock switch 180, closed contacts 148 of hand lock switch 133 to power line 111. The energization of vertical up relay 202 closes its contact 302 (Fig. 3) which energizes solenoid 88 to operate pilot valve 89 (Fig. 2) which operates valve 43 to admit oil under pressure from pump 36 through pipe 81, valve 43, through pipe 90, and foot valve 91 into the lower end of vertical cylinder 16 to move the piston 17 and vertical ram 18 upward. The die part 21 (Fig. 1) is thus moved upward to open the die 22 to permit breathing whereby any trapped air or gas in the mold may escape.

The energization of vertical up relay 202 also closes its contact 303 to operate the control relay 289 from power line 188 through conductor 304, the winding of relay 289, closed contact 303 of energized relay 202, conductors 305—306, closed contact 277 of energized control relay 268, conductor 307 to power line 187. The operation of control relay 289 closes its contact 308 to establish a locking circuit from power line 188 through conductor 304, the winding of relay 289, closed contact 308, conductors 309, 310, 306, closed contact 277, conductor 307 to power line 187. Energized control relay 289 also opens its contact 288 and closes its contacts 311 and 312.

After a predetermined interval when timer 263 times out, contact 296 is opened to deenergize vertical up relay 202, which opens contact 302 (Fig. 3) to deenergize up solenoid 88 which permits valve 43 (Fig. 2) to return to neutral position and stop the flow of oil through pipe 90 and thus discontinue the upward movement of vertical ram 18. Also, when timer 263 times out, a circuit through another timing mechanism 313 is completed from power line 188, through a conductor 314, winding of timer 313, conductor 315, normally closed contact 316 of an unoperated control relay 317, closed contact 312 of energized control relay 289, normally closed contact 318 of deenergized timer 263, conductors 319, 320, 301, 276, 271, closed contact 270 of up limit switch 94, conductors 269, 258, 255, closed contact 234 of energized vertical lock out relay

231, conductors 237, 195, closed contact 189, upper closed contact 194 of cycle lock switch 180 and closed contacts 148 of hand lock switch 133 to power line 111.

5 A locking circuit to maintain the timer 313 energized is established from power line 188 through conductor 314, the winding of timer 313, its closed contact 321, conductors 322, 295, 291, 292, 258, 255, closed contact 234 of energized vertical lock out relay 231, conductors 237, 195, closed contact 189, upper closed contacts 194 of cycle lock switch 180, closed contacts 148 of hand lock switch 133 to power line 111.

The operation of timer 313 closes its contact 323 which sets up a circuit to energize vertical down relay 200 from power line 188 through conductor 261, normally closed contact 260 of unoperated vertical up relay 202, the winding of vertical down relay 200, conductor 324, closed contact 323, conductors 325, 292, 258, 255, closed contact 234 of energized vertical lock out relay 231, conductors 237, 195, closed contact 189, upper closed contacts 194 of cycle lock switch 180, closed contacts 148 of hand lock switch 133 to power line 111.

Operated vertical down relay 200 closes its contact 330 which establishes a circuit from power line 188 through conductor 331, the winding of control relay 317, previously closed contact 311 of energized relay 289, conductor 332, closed contact 330 of relay 200, conductors 333, 324, 310, 306, closed contact 277 of energized control relay 268, conductor 307 to power line 187. Control relay 317 establishes a locking circuit from power line 188 through conductor 331, the winding of relay 317, conductor 335, closed contact 336 of energized relay 317, conductors 337, 338, 334, 310, 306, closed contact 277 of energized control relay 268, conductor 307 to power line 187.

40 Operation of vertical down relay 200 (Fig. 5) also closes its contact 264 (Fig. 3) to energized down solenoid 77 which operates its pilot valve 78 (Fig. 2) to operate valve 43 thereby causing oil under pressure to flow through pipes 82, 76 into the upper end of vertical cylinder 16. Ram 18 then moves down to apply pressure to the molding die 22 until the end of the cure of the molded article as determined by the timing mechanism 313.

50 At the end of the cure of the molded article in the molding die, the timer 313 times out thereby opening contact 323 to deenergize the vertical down relay 200 and stop the flow of oil under pressure into the upper portion of vertical cylinder 16. Timer 313 in becoming deenergized closes its contact 339 to establish an energizing circuit for vertical up relay 202 from power line 188 through conductor 297, the winding of relay 202, conductor 340, closed contact 341 of energized control relay 317, normally closed contact 339 of deenergized timer 313, conductors 342, 325, 292, 258, 255, closed contact 234, conductors 237, 195, closed contact 189, upper closed contacts 194 of cycle lock switch 180, upper closed contacts 148 of hand lock switch 133 to power line 111.

60 Energization of vertical up relay 202 effects the closing of its contact 302 (Fig. 3) which energizes up solenoid 88 (Fig. 2) to operate pilot valve 89. This pilot valve operates valve 43 to cause oil under pressure to flow through pipe 90 and past valve 91 into the lower end of cylinder 16 to cause the vertical ram 18 to move up until the up limit switch 94 (Fig. 2) is operated by the arm 93 on the rod 85, which travels with the vertical ram 18. Operation of limit switch 94 opens its

70 75 contact 302 which deenergizes up solenoid 88 and opens contact 302 which deenergizes vertical up relay 202.

13

normally closed contact 270 (Fig. 5) connected to power and thus deenergizes control relay 268, vertical up relay 202, control relay 289, and control relay 317 thereby stopping vertical ram 18 in its uppermost position.

The deenergization of control relay 268 opens its contact 279 and thus opens the locking circuit for horizontal in relay 217 to deenergize it. The deenergization of relay 217 opens its contact 230 (Fig. 3) to deenergize solenoid 52 (Fig. 2) to close pilot valve 63 which returns valve 42 to neutral position and thus shuts off the high pressure oil through pipe 58 into the horizontal cylinder 30 thereby removing pressure on the right hand side of horizontal piston 29.

Also the operation of up limit switch 84 closes its normally open contact 343 (Fig. 4) to establish a circuit from power line 187 through closed contacts 343, closed contact 344 of out limit switch 68, conductor 345, the winding of horizontal out relay 199, normally closed contact 346 of unoperated horizontal in advance relay 193, normally closed contacts 347 of unoperated horizontal in relay 217, conductor 348 to power line 188. The energization of horizontal out relay 199 closes its contact 350 (Fig. 3) to energize out solenoid 95 to actuate its pilot valve 96 (Fig. 2) to operate valve 42 which causes oil under pressure to flow from pump 37 through pipe 57, valve 42 and pipe 60 into the left end of horizontal cylinder 30 to move the piston 29 and horizontal ram 28 to the right toward "out" position until arm 61 (Fig. 2) on rod 62 traveling with the horizontal ram 28 operates the "out" limit switch 68 when movement stops with die 22 fully opened to permit removal of the molded article or mounting strip 23 (Fig. 6) therefrom.

The operation of limit switch 68 (Fig. 4) opens its normally closed contact 344 to open the energizing circuit to the horizontal out relay 199. The deenergization of relay 199 opens its contact 350 (Fig. 3) to deenergize out solenoid 95 (Fig. 2) to close pilot valve 96 which allows valve 42 to return to neutral. Valve 42 thus shuts off the oil under pressure through pipe 60 (Fig. 2) to stop the movement of the horizontal ram 28 in its outermost position to the right. The die 22 is then open and ready to be put through another cycle of pressing, breathing and repressing for predetermined intervals as controlled by the hydraulic, electrical and timing mechanisms as hereinbefore described.

Automatic cycling operation without breathing

When it is desired to omit the breathing portion of the cycle in operating the press, the breathing selector switch 351 (Fig. 5) is closed to establish a circuit from power line 187 through the winding of breathing out relay 250, conductor 352 to power line 188. The relay 250 operates to open its contacts 248, 290, which open the energizing circuits to timers 241 and 263 thereby rendering them non-operative. Relay 250 also closes its contacts 352, 353, which condition circuits to energize control relay 317 and timer 313, respectively, at the proper times.

With the breathing selector switch 351 closed to out position to eliminate the breathing cycle, the operation of the press proceeds as hereinbefore described for automatic cycling operation. That is, briefly summarizing the prior operations, the operator momentarily closes cycle lock switch 180 (Figs. 1 and 4) to energize the cycle control relay 141 which establishes and maintains an energizing circuit through its own interlock contact

14

186 whereupon the switch 180 is released to return to normal position to close its upper contacts 194. The operation of the cycle control relay 141 renders hand control non-operative and closes contacts 131—132 to connect power to lines 187 and 188 which lines are connected to the automatic control circuits of Figs. 4 and 5. The operator then closes horizontal control switch 192 to control the horizontal ram by energizing the horizontal in advance relay 193 which is maintained energized through its own interlocked contacts 205. The operation of the relay 193 energizes the fill motor relay 207 and horizontal in relay 217.

15 The operation of relays 193 and 217 controls the operation of contacts 215 and 230 (Fig. 3) to energize horizontal in solenoids 45 and 52, which in turn controls hydraulic valves 41 and 42 (Fig. 2) as hereinbefore described to admit oil, under pressure, into the right end of horizontal cylinder 30 to move the horizontal ram 28 toward the left to "in" position. The horizontal ram as it closes, the die parts 24, 26 operates limit switch 63 to open the energizing circuit for relay 193 which opens contact 215 to deenergize solenoid 45 to return hydraulic valve 41 to non-operative neutral position but permits valve 42 to continue to apply oil under pressure to the right end of the horizontal piston 29 to keep die parts 24, 26 closed. The horizontal ram also operates limit switch 65 which sets up an energizing circuit to actuate vertical lock out relay 231 and close its contact 234 to power.

35 The die is now closed, molding material is introduced, and the operator then closes vertical control switch 235 (Fig. 5) to effect operation of vertical down advance relay 236, which is maintained energized by a locking circuit from power line 188 through conductor 240, normally closed contact 239, the winding of relay 236, conductor 241, closed contact 242, conductor 243 through closed limit switch 83 (Figs. 2 and 4) to power line 187.

40 The operation of vertical down in advance relay 236 closes its contact 246 (Fig. 3) to energize down advance solenoid 70 which operates valve 41 (Fig. 2) to send oil under pressure through pipes 75, 76 into the upper end of cylinder 16 to move the vertical ram 18 downward.

50 The closure of vertical control switch 235 and the previous closure of contacts 353 by the energized breathing out relay 250 establishes a circuit from power line 188 through conductor 314, the winding of timer 313, conductor 354, closed contact 353, conductor 355, closed contacts 244 of switch 235, closed contacts 234 of operated vertical lock out relay 231, conductors 237, 195, closed contact 189, upper closed contacts 194 of cycle lock switch 180, closed contacts 148 of unoperated hand lock switch 133 to power line 111. Timer 313 is thus energized to close its contacts 321 and 323, and also opens its contact 339 (Fig. 5).

65 The timer 313 is maintained energized through the closure of its contact 321 by a locking circuit from power line 188 through conductor 314, the winding of timer 313, its closed contact 321, conductors 322, 285, 291, 292, 258, 255, closed contact 234 of energized vertical lock out relay 231, conductors 237, 195, closed contact 189, upper closed contacts 194 of cycle lock switch 180, upper closed contacts 148 of hand lock switch 133 to power line 111.

70 The vertical down relay 200 is also energized

to assist in the downward movement of ram 18 by a circuit from power line 188 through conductor 261, normally closed contact 260 of deenergized vertical up relay 202, the winding of vertical down relay 200, conductor 324, closed contact 323 of energized timer 313, conductors 325, 292, 258, 255, closed contact 234 of energized relay 231, conductors 237, 195, closed contact 189, upper closed contacts 194 of cycle lock switch 180, upper closed contacts 148 of hand lock switch 133 to power line 111.

Vertical down relay 200 thus operates and closes its contact 264 (Fig. 3) to energize the down solenoid 71 which operates pilot valve 78 and valve 43 to send high pressure, low volume oil through pipes 82, 76 into the upper end of cylinder 16 to assist in the downward movement of vertical ram 18.

The dual operation of down solenoids 70 and 71 continues to control the downward movement of vertical ram 18 until the arm 84 on the rod 85 moving with the ram operates limit switch 83 to open the previously described locking circuit through conductor 243, contact 242, conductor 241 and deenergize the vertical down advance relay 236, which then opens its contact 246 (Fig. 3) to deenergize solenoid 70. The vertical down relay 200 is continued energized to maintain solenoid 71 operated to apply molding pressure to the die through ram 18 until the timer 313 times out when its contact 323 is opened to deenergize the vertical down relay 200 which then opens contact 264 to deenergize solenoid 71 and release downward pressure on the vertical ram 18.

The energization of vertical down relay 200 closed its contact 267 to establish a circuit from power line 188 through conductor 273, the winding of control relay 268, its closed contact 267 of energized relay 200, conductors 272, 271, closed contact 270 of limit switch 94, conductors 269, 258, 255, closed contact 234, conductors 237, 195, closed contacts 189, 194, 148 to power line 111. Control relay 268 operates and closes its contacts 279, 274, 277, 278, and opens its contact 224 (Fig. 4).

A locking circuit for energized relay 268 is established from power line 188 through conductor 273, the winding of relay 268, its closed contact 274, conductors 275, 276, 271, closed contact 270 of limit switch 94, conductors 269, 258, 255, closed contact 234, conductors 237, 195, closed contact 189, closed contacts 194 of cycle lock switch 180, closed contacts 148 of hand lock switch 133 to power line 111.

The closing of contact 277 by the operation of relay 268 establishes a circuit from power line 187 through conductor 307, closed contact 271, conductors 306, 310, 334, 338, 358, closed contact 352 of energized breathing out relay 250, conductors 359, 335, the winding of control relay 317, conductor 331 to power line 188. Control relay 317 operates to close its contacts 341, 336 and open its contact 316.

The closing of contact 341 establishes an energizing circuit for vertical up relay 202 from power line 188 through conductor 297, the winding of relay 202, conductor 340, closed contact 341, normally closed contact 339 of unoperated timer 313 which has timed out, through conductors 342, 325, 282, 258, 255, closed contact 234, conductors 237, 195, closed contact 189, closed contacts 194 of cycle lock switch 180, closed contacts 148 of hand lock switch 133 to power line 111.

The energization of up relay 202 (Fig. 5)

causes the closing of its contact 302 (Fig. 3) to energize up solenoid 88 which operates pilot valve 89 (Fig. 2) and valve 43 to cause oil under pressure to pass through pipe 90 and foot valve 91 into the lower end of cylinder 16 to move vertical ram 18 and die part 21 upward to open the die 22.

When the vertical ram 18 reaches its upper limit switch 94 is operated to open contact 270 (Fig. 5) and deenergize up relay 202 which opens its contact 302 (Fig. 3) to deenergize up solenoid 88. The deenergization of solenoid 88 closes pilot valve 89 (Fig. 2) to permit valve 43 to return to neutral position to shut off the oil through pipe 90 and stop the movement of ram 18 in its uppermost position. The operation of the cycle then proceeds to move the horizontal ram to "out" position, thus opening the die for removal of the molded article and the press is now ready for another operating cycle.

Cycling of vertical ram only

To obtain operation of the vertical ram 18 without operating the horizontal ram 28, the operator turns the vertical switch 219 (Fig. 4) to on position to open its contact 218 and close its contact 360. The opening of contact 218 renders horizontal in relay 217 non-operative for the horizontal ram 28. The closing of contact 360 establishes an energizing circuit for vertical control relay 142 from power line 111 through closed contact 360, the winding of relay 142, normally closed interlocking contact 361 of unoperated horizontal control relay 143, conductor 362 to power line 112. Vertical control relay 142 operates and opens its interlocking contact 139, 363, 196 to render both hand and automatic controls non-operative for the horizontal ram 28 so that it cannot be operated. Relay 142 also closes its contacts 364 and 365. The closure of contact 365 by-passes open limit switch 65 to energize vertical lock out relay 231 from power line 187 through the winding of relay 231, conductor 366, closed contact 365, conductor 233 to power line 188. Cycle vertical switch 235 is then closed momentarily to energize vertical down advance relay 236 which closes its contact 368 (Fig. 4) to establish an energizing circuit for the fill motor relay 207 from power line 187 through closed limit switch 83, conductor 367, closed contact 364 of relay 142, closed contact 368 of energized vertical down advance relay 236, conductors 369, 209, the winding of fill motor relay 207, the closed contact 210 of energized main motor relay 119 to power line 188. Relay 207 then closes its contact 213 (Fig. 3) to effect operation of pump motor 40 and high volume, low pressure pump 39.

Energization of vertical down advance relay 236 closes its contact 246 (Fig. 3) to energize down advance solenoid 70. Solenoid 70 then operates pilot valve 71 (Fig. 2) to actuate valve 41 which causes oil under pressure to pass through pipes 75, 76 into the upper end of vertical cylinder 16 to move piston 17 and vertical ram 18 downward.

Thus with the closing of vertical switch 219 and cycle vertical switch 235, automatic cycling of the vertical ram 18 can be had either with or without breathing, depending upon the position of the breathing selection switch 351 (Fig. 5). The sequence of operations then occurs as previously described in detail for the operation of the vertical ram.

Operation of horizontal ram only

In setting up the machine with molding dies it is often desirable as a protective measure to render the vertical ram non-operative when the horizontal ram is being manually controlled. When it is desired to operate only the horizontal ram under manual control, a horizontal switch 370 (Fig. 4) is closed to energize the horizontal control relay 143 from power line 111 through closed horizontal switch 370, conductor 371, closed contact 363 of unoperated vertical control relay 142, the winding of relay 143, conductor 372 to power line 112. The horizontal control relay 143 operates and opens its interlocking contacts 140, 184 and 361 to render inch vertical down relay 158, inch vertical up relay 159, cycle control relay 141 and vertical control relay 142 non-operative. Thus upon the closures of horizontal switch 370 and of hand lock switch 133 the horizontal ram 28 can be manually controlled in its movement by the selective operation of button switches 152 or 170, while at the same time rendering it impossible to move vertical ram 18 because of the opening of the above described interlocking contacts 140, 184 and 361.

Emergency stop

The molding press is equipped with an emergency switch 181 (Figs. 1 and 4) which when opened deenergizes cycle control relay 141. The deenergization of relay 141 opens its interlocking contacts 186, 131, 189 and 132 to render all control circuits ineffective and return all of the hydraulic valves 41, 42 and 43 to neutral and thus stop the operation of both rams 18 and 28 immediately. The cycling control relay 141 cannot be brought back into operation until cycle lock switch 180 is again manually closed. The normally open contact 183 of out limit switch 68 also prevents operation of the cycle control relay 141 unless the horizontal ram 28 (Fig. 2) is all the way out to the right to close its contact 183.

It is to be understood that while the embodiment disclosed and described herein is a preferred one, the invention is susceptible to many different forms, and that other instrumentalities may be substituted for those disclosed, and that various changes and modifications may be made without departing from the spirit and scope of this invention as defined by the appended claims.

What is claimed is:

1. In a system for controlling hydraulic pressures, a first pump for delivering high volume low pressure fluid, a second pump for delivering high pressure low volume fluid, separate means for driving each of said pumps, a cylinder, a ram operated from the cylinder and controlled by the fluids from said pumps, means for connecting both pumps to the cylinder to move the ram at fast speed, means for stopping the driving means for the first pump to move the ram at slow speed, and an electrical circuit including a plurality of solenoids selectively controlled by the position of said ram for controlling the said plurality of connecting means to move the ram at selected intervals and at predetermined speeds and pressures.

2. In a hydraulic system for controlling the operation of a ram in a press, a prefill pump for operating the ram at high speed, a motor for operating the prefill pump, means for operating the ram at slow speed, and means for stopping the prefill pump motor upon the attaining of a predetermined condition so that only the means for operating the ram at slow speed is effective.

3. In a system for controlling an angle molding press having a vertical ram and a horizontal ram, means for supplying high volume low pressure hydraulic power to the rams to operate them at high speed, means for supplying low volume high pressure hydraulic power to the rams to operate them at slow speed, separate means for driving the hydraulic power means, and an electrical circuit controlled by the position of each of said rams for rendering the driving means and the hydraulic power means selectively effective singly and simultaneously to control the operation of the rams at predetermined speeds and at predetermined intervals.
- 15 4. In an angle molding press, a horizontal ram, a vertical ram, means for moving the horizontal ram at high speed, means for moving the horizontal ram at slow speed, means for moving the vertical ram at high speed, means for moving the vertical ram at slow speed, pilot controlled directional valves for controlling all of said moving means, means at a predetermined position in the path of movement of each of the rams for controlling said valves to render the high speed moving means ineffective and the slow speed moving means effective, and means at a second predetermined position in the path of movement of the rams for rendering the slow moving means ineffective after the ram has been moved slowly for a predetermined distance.
- 20 5. In an angle molding press, a horizontal ram, a vertical ram, a plurality of means for operating the horizontal and vertical rams, manual control means for controlling the operating means for each ram separately, control means for cycling the vertical ram independently of the operation of the horizontal ram, interconnecting means for rendering the manual control means inoperative for said horizontal ram while the vertical cycling control means operates the vertical ram, automatic cycling control means for simultaneously controlling the operating means for both of the rams, and means for interlocking the manual control means and the automatic cycling means to permit the operation of only one of said control means at a time.

6. In an angle molding press, a horizontal ram, a vertical ram, means for actuating the horizontal ram, a first control means for manually controlling said horizontal actuating means to control the movement of the horizontal ram, means for actuating the vertical ram, a second control means for controlling the vertical actuating means to cycle the vertical ram independently of the horizontal ram, and selective means for rendering only one of said electrical circuits effective at one time so as to operate the rams independently of each other.

7. In an angle molding press, a horizontal ram, a vertical ram, a plurality of means for actuating each of the rams, an electrical system for controlling the actuating means including a first electrical circuit for manually controlling reciprocations of the horizontal ram, a second electrical circuit for automatically controlling reciprocations of the vertical ram in successive cycles, a plurality of interlocking switches selectively operable in the electrical system for rendering only one of said electrical circuits effective at a time, and an emergency switch for rendering the interlocking switches, the electrical system and the ram actuating means ineffective.

8. In a molding press, a ram, a first pump for moving the ram at fast speed to a predetermined point, a second pump for moving the ram at slow

speed, means at said predetermined point for rendering the fast moving pump ineffective and the slow moving pump effective for the ram, means at a second predetermined point in the movement of the ram for rendering the slow moving pump ineffective after it has moved the ram a predetermined distance, and means at a third predetermined point in the movement of the ram for limiting the retraction of the ram.

9. In an angle molding press for operating a three-part molding die, a horizontal ram, a vertical ram, means for moving the horizontal ram to close two of the die parts, means for moving the vertical ram down to close the third die part with the other two closed die parts, means for controlling said moving means for the vertical ram so that the vertical ram applies pressure to the die for a first predetermined interval, means for elevating said vertical ram at the end of said predetermined interval to permit the die to breathe, timing means for maintaining said vertical ram in an elevated position for a second predetermined interval, and means to move said vertical ram down at the end of the second predetermined interval to again apply pressure to the die.

10. In an angle molding press for operating a three-part molding die, a horizontal ram, a vertical ram, means for moving the horizontal ram to close two of the die parts, means for moving the vertical ram down to close the third die part with the other two closed die parts, timing means for maintaining the die closed for a first predetermined interval, means for elevating the vertical ram at the end of said predetermined interval to permit the die to breathe, means for maintaining said vertical ram in its elevated position for a second predetermined interval and thereafter to reclose the die, and selectively operable means for rendering the elevating means and the reclosing means ineffective so that the horizontal and vertical moving means may be operated without the elevating and reclosing operation.

11. In an angle molding press, a horizontal ram, a vertical ram, means for moving the horizontal ram, means for moving the vertical ram, means for controlling the horizontal moving means to move the horizontal ram at fast speed, means effective at a predetermined position in the travel of the horizontal ram to render the fast speed control means ineffective and move the horizontal ram at slow speed, a limit switch in the path of movement of the horizontal ram for stopping it and rendering the vertical ram moving means effective at fast speed, means effective at a predetermined position in the travel of the vertical ram for controlling its moving means to move the vertical ram down at slow speed, a timing mechanism for controlling the vertical ram moving means to move the vertical ram up after a predetermined interval, and means for rendering the vertical ram moving means ineffective when the vertical ram reaches its uppermost position and for rendering the horizontal ram moving means effective to move the horizontal ram at fast speed.

12. In an angle molding press for operating a three-part molding die, a horizontal ram for closing two parts of the die, a vertical ram for closing the third part of the die, means for moving the horizontal ram, means for moving the vertical ram, means for rendering the horizontal moving means effective to close the two die parts and stop, means operated by the horizontal ram when the two die parts are closed for rendering

the vertical ram moving means effective to move the ram down to close the third part of the die and apply molding pressure, a timing mechanism for rendering the moving means effective to move the vertical ram up to open the die at a predetermined time, means effective after a predetermined interval for again controlling the vertical moving means to move the vertical ram down to close the die and apply a molding pressure, another timing means effective after a predetermined interval to effect movement of the vertical ram upward, and means for stopping the vertical ram in its uppermost position and for controlling the horizontal ram moving means to move the horizontal ram to open the molding die.

13. In an angle molding press for operating a three-part molding die to compress a molding material into a molded article, a horizontal ram carrying a part of the molding die, a vertical ram carrying another part of the molding die, means for moving the horizontal ram to close and hold two parts of the molding die together, means for moving the vertical ram to bring the third part of the molding die into closing relationship with the other two die parts, a plurality of valves for controlling the moving means for the said rams, a horizontal in solenoid for operating a valve to move the horizontal ram to in position to close two of the die parts, a horizontal out solenoid for controlling a valve to move the horizontal ram to out position to open the molding die, a vertical up solenoid for controlling a valve to move the vertical ram up to open the molding die, a vertical down solenoid for controlling a valve to move the vertical ram down to close the die and apply molding pressure to the molding material, and electrical controlled means for operating the said solenoids in a predetermined sequence and at predetermined intervals to move the rams to close the die to apply a given molding pressure, then release the molding pressure to permit breathing for the escapement of gases, reapplying molding pressure, and subsequently retracting the rams to open the molding die to release the molded article.

14. In an angle molding press, a vertical ram, a horizontal ram, means for actuating the vertical ram, means for actuating the horizontal ram, a first limit switch in the path of movement of the vertical ram for rendering the vertical ram actuating means ineffective when the ram reaches its uppermost position and for rendering the horizontal ram actuating means automatically effective to move the horizontal ram, a second limit switch positioned in the path of movement of the horizontal ram for rendering the vertical ram actuating means effective to move the vertical ram, means for maintaining the vertical ram actuating means ineffective so that the vertical ram remains at its uppermost position until the horizontal ram actuates said second limit switch, and a third limit switch in the path of movement of the horizontal ram for controlling the horizontal actuating means to maintain pressure on the horizontal ram while the vertical ram moves downward.

15. In an angle molding press using a multi-part die, a vertical ram for moving a die part, a horizontal ram for moving a die part, means for moving the vertical ram, means for moving the horizontal ram, a plurality of solenoids for controlling the ram actuating means to determine the down and up movement of the vertical ram and the in and out movement of the horizontal

ram, relays for controlling the solenoids, a plurality of timing devices for controlling the time of operation of predetermined relays, limit switches associated with each ram and electrically connected to predetermined relays, and means to energize the relays in a predetermined sequence to control the operation of the solenoids to render the ram actuating means effective to move the rams and the die parts through a given cycle as determined by the timing devices and the operation of the limit switches, means to elevate and reclose the vertical ram to permit the die to breathe, selectively operable means to control the vertical moving means to reciprocate the vertical ram in successive cycles independent of the horizontal ram, and interlocking switches for rendering the breathing means ineffective to cycle the vertical ram without breathing.

16. In an angle molding press for operating a three part die, a horizontal ram, a vertical ram, a plurality of means for operating the horizontal and vertical rams, manual control means for actuating the operating means to move the horizontal ram to close two of the die parts, manual control means for actuating the operating means to move the vertical ram down to close the third part of the die, and interlocking means effective upon actuation of one of the manual control means to prevent operation of the other manual control means.

17. In an angle molding press for operating a three part molding die, a horizontal ram, a vertical ram, a first manually controlled means for moving the horizontal ram to close two of the die parts, a second manually controlled means for moving the horizontal ram to open two of the die parts, a third manually controlled means for moving the vertical ram to close the third part of the die with the other two parts, a fourth manually controlled means for moving the vertical ram to separate and open the third part of the die from the other two parts, and means for interlocking all of the manually controlled means so that when one of them is operated the others are rendered incapable of operation.

18. In an angle molding press, a horizontal ram, a vertical ram, a low pressure-high volume pump, a high pressure-low volume pump, means to connect both of said pumps to either one of said rams for moving the particular ram at a high speed to a predetermined point, means positioned at said predetermined point for disconnecting the low pressure-high volume pump so that only the high pressure-low volume pump is effective to move the particular ram at a slow speed, and means to prevent the simultaneous operation of both rams at high speed.

19. In an angle molding press, a ram, a plurality of electric motors, a control circuit for each of the electric motors, a plurality of pumps each driven by a particular one of said motors, said pumps supplying fluid pressure to drive the ram, and means controlled by the movement of the ram to interrupt the circuit to one of the electric motors to render one of the pumps non-operative so that the movement of the ram continues at a reduced rate of speed.

20. In an angle molding press for operating a three part die, a horizontal ram for closing two parts of the die, a vertical ram for closing the third part of the die with the other two parts in closed position, a hydraulic pressure system for supplying fluid under pressure to operate the rams, an electrical control circuit for controlling the hydraulic pressure system comprising a plu-

rality of limit switches spaced along the path of travel of each of the rams and operated by the movement of the rams, one pair of said switches rendering a portion of the hydraulic system ineffective for each of the rams, a second pair of said switches rendering the entire hydraulic system ineffective for each of said rams, and a third pair of said switches electrically interconnecting the hydraulic system so that the movement of each of the rams is controlled by them ovement of the other ram, and a plurality of time delay relays for controlling the time and direction that the pressure is supplied by the hydraulic system to the vertical ram.

15. 21. In an angle molding press, a horizontal ram, a vertical ram, means for supplying hydraulic power to move the rams, a first automatic electrical control circuit for controlling the supply of hydraulic power to the horizontal and vertical rams to simultaneously move them through a cycle of operations, a second automatic electrical control circuit for controlling the supply of hydraulic power to the vertical ram to move it through a cycle of operations, manual control means for controlling the supply of power to each of the rams to move either one in a single direction, and selective means for rendering only one of the control means effective at any one time.

20. 22. In an angle molding press having an electrically controlled hydraulic system for operating a multi-part molding die, a horizontal ram for moving one die part into closing engagement with a second die part, a vertical ram for closing the third part of the die with the two other die parts, electrically controlled hydraulic means for moving the horizontal ram to close the two die parts and stop, electrically controlled hydraulic means operated by the horizontal ram when the

25. 40. two die parts are closed to move the vertical ram down to close the third part of the die and apply molding pressure, electrical timing means for repeatedly rendering the hydraulic moving means effective to move the vertical ram up a predetermined distance to open the die after predetermined timed intervals, other electrical timing means for maintaining the die open for predetermined intervals and thereafter to close the die and apply molding pressures repeatedly to the die, electrical means for stopping the vertical ram

30. 50. 45. 55. in its upper open position after a predetermined number of cycles of up and down movements thereof and for moving the horizontal ram to open the die on completion of the molding operation, and electrical interlocking means for operating any ram independent of the other ram.

Certificate of Correction

Patent No. 2,567,715

September 11, 1951

EDWIN F. KEUSCH ET AL.

It is hereby certified that error appears in the printed specification of the above numbered patent requiring correction as follows:

Column 10, line 33, for "275" read 272; column 12, line 31, for "324" read 334; column 14, line 68, for "time" read *timer*;

and that the said Letters Patent should be read as corrected above, so that the same may conform to the record of the case in the Patent Office.

Signed and sealed this 22nd day of January, A. D. 1952.

[SEAL]

THOMAS F. MURPHY,
Assistant Commissioner of Patents.
